United States Patent Office

Des. 196,427
Patented Oct. 1, 1963

196,427

TRAILER

Arthur I. Anderson, St. Paul, and Keith F. Solimar,
Minneapolis, Minn., assignors to Butler Manufacturing
Company, Kansas City, Mo., a corporation of Missouri

Filed Aug. 3, 1962, Ser. No. 71,165

Term of patent 14 years

(Cl. D14—3)

FIG. 1 is a perspective view of a trailer embodying our new design;

FIG. 2 is a front elevational view of same;

FIG. 3 is a rear elevational view of same;

FIG. 4 is a top plan view of same; and

FIG. 5 is a side elevational view of same taken from the right hand side of FIG. 2, the other side being substantially identical thereto.

The dominant features of the design reside in the portion shown in full lines.

We claim:

The ornamental design for a trailer, as shown and described.
